UNITED STATES PATENT OFFICE.

FRED MIKEAL, OF JACKSBORO, TEXAS.

CAR-COUPING.

No. 918,764.

Specification of Letters Patent. Patented April 20, 1909.

Application filed June 24, 1907. Serial No. 360,648.

To all whom it may concern:

Be it known that I, FRED MIKEAL, a citizen of the United States of America, and a resident of Jacksboro, county of Jack, State of Texas, have invented certain new and useful Improvements in Car-Couplers, of which the following is a specification.

My invention relates to car couplers and more particularly to that type in which a coupling-pin and link are employed and the striking together of the coupling heads causes the pin to drop through the link and effect the coupling without necessitating a trainman being present.

The object of this invention is to provide an improvement in the means whereby the pin can be set preparatory to coupling, and automatically released by the contacting of the coupling heads.

To that end it consists in the construction, arrangement and combination of parts which are hereinafter more fully described and claimed.

In the accompanying drawings which form a part of this specification:—Figure 1 is a side elevation of a coupling head, having my invention applied thereto, the coupling pin being set. Fig. 2 is a side elevation of the same with the coupling pin released, and Fig. 3 is a plan of the showing of Fig. 2.

Coupling head 1 has projecting inwardly from its face, a flared mouthed horizontal coupling-link chamber 2, and, extending therethrough from the top a vertical coupling-pin chamber 3, immediately behind which lies a vertical aperture 4.

Suitably journaled to the bottom of the coupling head, in brackets 5 and 5^a, the latter of which may be integral with the head if desired, is a crank shaft 6, extending to the side of the car and being provided on its outer end with an arm and handle 7, and midway between brackets 5 and 5^a with forwardly extending arm 8. Ratchet wheel 20 is firmly mounted upon said crank shaft adjacent to the side of the head. Pivoted at the end of arm 8 is the link 9 which extends upwardly through aperture 4 (the latter being large enough to permit free play), and has its upper end bent forward and bifurcated for the reception and pivoting of the upper end of coupling-pin 10. Coiled-spring 11 encircles crank shaft 6 and has its middle portion approximately straight and abutting against the upper side of the arm 8, its side portions oppositely coiled, and its

ends abutting against the lower face of head 1 in such a manner as to exert a downward pull on arm 8.

Rod 16 is suitably mounted upon the exterior of head 1, in brackets 15, and is pressed outwardly by coiled-spring 17, its outer end projecting slightly beyond the face of the head and its inner end having pivoted thereto one end of link 18, the other end of which is pivoted to pawl 19, which latter is in turn pivoted to the side of head 1 in such a position as to engage the tooth of the ratchet 20, and thus prevent clock-wise rotation of crank shaft 6 when the coupling-pin 10 is raised into a proper setting position. Thus it is evident that the pawl 19 constitutes a brake lever for the vertical rod 9.

Any convenient means can be employed whereby the coupling-pin 10 can be raised from the top of the car. In the particular embodiment of my invention herein shown such means consist of a link 13 pivoted at the bottom to link 9, and at the top to one end of the lever 14, by depressing the other end of which, it is obvious the coupling-pin will be raised.

The operation of the device is as follows:—When it is desired to make a coupling, the trainman, if at the side of the car, turns the crank counter clockwise until, by means of link 9, the lower end of coupling-pin 10 is raised just above the link chamber 2, the parts 6, 7, and 8 thus constitute a setting lever for the pin. In this position the pawl 19, properly positioned and maintained by coiled-spring 17, engages the tooth of ratchet wheel 20 and holds the coupling-pin thus suspended. If the trainman is on top of the car, he accomplishes the same result by means of lever 14 and link 13. The cars to be coupled are then brought together, the coupling-link on the other car enters the flared mouth link chamber 2, and its coupling head striking the rod 16, pushes it inwardly and thus causes pawl 19 to be withdrawn from the tooth of ratchet wheel 20, and the coupling-pin 10, due to its weight and the tension of spring 11 transmitted through arm 8 and link 9, drops through the coupling link and effects the coupling.

What I claim and desire to secure by Letters Patent is:—

1. In a car-coupler, the combination with a coupling-pin, of a vertically movable rod adapted to lift the said pin, a crank shaft co-operating therewith, a ratchet wheel mount-

ed on said shaft, a pawl adapted to hold said ratchet wheel against rotation, a link pivoted thereto, and a pin pivoted to said link mounted upon the coupling head and projecting forwardly from the face thereof, substantially as described.

2. In a car coupler the combination with a coupling pin, of a vertically movable rod adapted to lift the said pin, a brake lever pivoted intermediate of its ends, and one end restraining the said rod, a releasing pin projecting beyond the face of the coupler and connected by a link to the other end of the brake lever, and a spring tending to throw the brake lever to hold the vertical rod, substantially as described.

3. In a car coupler the combination with a suitable head having a link chamber in the forward face thereof and a vertical bore ex-

tending through the head in the rear of said chamber, of a coupling pin, a rod vertically movable in the said bore and engaging the said pin, a setting lever pivoted below the coupler in the rear of the said rod, and pivoted to the latter, a brake lever for the rod pivoted on the head, a releasing pin mounted on the head, and connected by a link to one end of the brake lever, and a coiled spring tending to project the releasing pin beyond the forward face of the coupler and acting on the brake lever to hold the vertical rod raised.

Signed at Jacksboro this 1st day of June 1907.

FRED MIKEAL.
